UNITED STATES PATENT OFFICE.

GEORGE E. NEUBERTH, OF NEWARK, NEW JERSEY.

HINGE.

1,149,213.

Specification of Letters Patent.

Patented Aug. 10, 1915.

Application filed March 27, 1915. Serial No. 17,378.

To all whom it may concern:

Be it known that I, GEORGE E. NEUBERTH, a citizen of the United States, and a resident of Newark, county of Essex, and State 5 of New Jersey, have invented certain new and useful Improvements in Hinges, of which the following is a specification.

This invention relates to an improved hinge which permits a vertical movement of 10 one part thereof in relation to the other, the two parts of the hinge being thus adapted to allow the door to be raised to be removed from the hinge entirely or to be partly raised therefrom as in the case where this 15 hinge is used in conjunction with the kind of hinge that is operated by a handle to raise or lower a window or the like to place it in and out of a groove or any similar receiving structure.

20 The invention is designed to provide a hinge which secures the knuckles on a pintle without necessarily giving them any vertical movement whereby the pintle can be permanently headed or so headed that it 25 will not ride up out of place, as is very often the case with pintles having a head only on one end, so that the five points of contact are always available to give a good bearing and to hold the knuckles in proper 30 position.

The invention further provides means for attaching the slide of the hinge to a door or like fixture so that the fastening means are concealed when the slide is in place, and 35 the slide can be further constructed to provide means for preventing lateral movement of the slide on the door or the like so as to remove excessive shearing strain from the screws that hold the door in place. This 40 hinge is further adapted for use in conjunction with fireproof doors of metal or of wood covered with metal, since the slide is so arranged that it can be bolted or otherwise fastened straight through the door so 45 that the danger of burning away from the screws, as is sometimes the case with iron covered wooden doors, is not present when this form of hinge is used with a bolt or any similar fastening that is passed through 50 the slide and is fastened to the other side of the door.

The invention is illustrated in its preferred form in the accompanying drawing, in which—

55 Figure 1 is a front view of the hinge. Fig. 2 is an edge view of the hinge shown

in Fig. 1 with the top part of one of the hinge leaves and the slide in section. Fig. 3 is a top view of the hinge shown in Fig. 1 with the leaf and a part of the slide shown 60 in section taken through one of the screw holes in the slide.

In the form shown the hinge leaves are hinged together on a pintle, one hinge leaf 10 being of the usual butt type and having 65 screw holes 11 by means of which it is fastened to a frame or similar structure, and being provided with knuckles 12 which are spaced apart to receive the knuckles 13 of a leaf 14, the knuckles being perforated 70 and receiving a pintle 15, and since in this type of hinge it is not necessary for the knuckles of one leaf to move longitudinally along the pintle, a five-knuckle or a hinge 75 can be used which provides good bearing 80 and long contact, and the heads 16 can therefore be fastened to the ends of the pintle in a permanent or somewhat permanent manner, in the form shown these heads being screwed as at 17 to the ends of the pintle. 85 In the ordinary form of hinge where the pintle is set in from the top and is not fastened at the bottom, it will very often ride up and makes a poor finish and also makes a harder working hinge because the knuckles 90 are not engaged by the pintle when the pintle rides up far enough. The pintles are usually made without fastening means at the bottom because it is usual to withdraw the pintles upward so as to separate the 95 leaves of the hinge when the door is to be removed, but in this construction it is not necessary to remove the knuckles from the pintle so that the pintle can be permanently put in place.

95 The leaf 14 is provided with a part 18 which can be disposed in any desired manner, but in the form shown it is formed at right-angles to the leaf 14 so as to form an L-shaped leaf and it is provided with a 100 guideway 19 opening at the back thereof in a reduced portion 20 so as to retain the slide which fits therein by having the outermost part of the guideway narrower than the inner portion. The slide 21 fits in the guideway 20 and slides vertically therein, the slide 21 being prevented from having any forward movement by reason of the guideway not being put to the front of the leaf so that a front wall 22 is formed opposite 110 the front of the slide.

To provide means for limiting the vertical

or what might be termed the inward movement of the slide, different means can be devised, but I prefer to limit the inward movement of the slide by forming a lip 23 at the 5 top of the slide which extends forward on top of the wall 22 and by its engagement therewith it prevents it from any further downward movement. To fasten the slide to the door, window or other suitable element, I provide screw holes, such as 24, which need not necessarily be of the type shown, these screw holes being hidden when the slide is in place and being adapted to receive screws or bolts to be fastened to the 10 door. To prevent excessive shearing or side strain on the screws I provide bosses which can be suitably disposed, but are preferably arranged concentric to the screw holes, these bosses 25 projecting from the 15 rear of the slide and being of any desired shape but preferably round so as to make it easy to provide recesses in the door for them by means of an ordinary slide. When these bosses are set in suitable recesses in the door they act to bear thereon and to prevent side movement of the door relative to the slide and thus assume the transverse strain which might come on the screws without these bosses.

20 It will be evident that when this hinge is fastened to a door and its frame, or to similar structures, the door can be lifted from the hinge by swinging the door open and then giving it a vertical lift until the slide 25 is disengaged from the part 18 of the hinge leaf, and it can be just as easily attached to the hinge by reversing the above described movements.

30 These hinges are desirable because there is 40 always the full five point bearing on the pintle and there is no vertical movement on

the pintle and consequently less tendency to loosen the screws.

Having now described my invention, I claim:

1. A hinge comprising a pair of leaves, one of the leaves having a guideway on its rear face, a slide fitting in the guideway, the part of the slide fitting in the guideway having means adapting it to be secured to an element to be supported, said means being concealed by said leaf when the slide is in place, and co-acting means on the slide and on the leaf in which it slides to limit the 50 sliding of the slide.

2. A hinge comprising a pair of leaves, one of the leaves having a guideway on its rear face, the guideway being narrowed at its outer portion, a slide in the guideway, the part of the slide fitting in the guideway 60 having holes therein for the reception of screws or the like, bosses on the rear of said slide and surrounding the screw holes, and means for limiting the sliding movement of the slide in the guideway.

3. A hinge comprising a pair of leaves, one of said leaves having a guideway on its rear face, and a slide in said guideway, the slide having a projecting lip to engage the top edge of the leaf to limit the downward 70 movement of said slide, the slide having screw holes therein, said screw holes being concealed by said leaf when the slide is in place, the slide having bosses on its rear face.

In testimony that I claim the foregoing, I hereto set my hand this 26th day of March, 1915.

GEORGE E. NEUBERTH.
